PHONOGRAPH RECORD RESURFACING
MACHINE

Charles Huenlich, Bloomfield, N. J., assignor to
Thomas A. Edison, Incorporated, West Orange,
N. J., a corporation of New Jersey

Application April 18, 1939, Serial No. 268,471

12 Claims. (CL 82—1.1)

This invention relates to machines for resurfacing phonograph records, and more particularly to improvements in such machines as are used to resurface phonograph records of the type employed in commercial phonographs or dictating machines. In some respects this invention has certain features in common with those disclosed in my copending application Serial No. 216,886, filed July 1, 1938 and entitled "Phonograph record shaving machines" and also with those disclosed in the copending applications of Richard M. Somers, Serial Nos. 215,948 and 232,766, respectively filed June 25, 1938 and October 1, 1938, and each entitled "Phonograph record shaving machines", which applications are connected by common ownership with the present application.

Phonograph record resurfacing machines of the form above-mentioned comprise a record-supporting mandrel, an endgate for the mandrel, a carriage bearing a resurfacing tool settable into operative position relative to a record on the mandrel, and driving means operable to rotate the mandrel and coincidentally move or feed the carriage along the mandrel from a start to a terminal position to cause the tool to traverse the record. Such tool-record traversal will cause a first or heavy cut to be taken from the record as whenever the tool is set into operative position. For the convenient operation of the machine the driving means is automatically rendered inoperative when the carriage is in its terminal position, the driving means being otherwise normally controlled by a control means manipulatable into "on" and "off" positions to start and stop the machine. In order that the carriage may be manually returned to start position, as for another tool-record traversal, it is arranged so that it may be disengaged from its feeding means, this disengagement being commonly effected by an upward tilting of the carriage from normal operative position. To permit the taking of a light or finishing cut after a first or heavy cut has been taken, there is provided a finishing-cut controlling means for advancing the tool a predetermined distance towards the record. In taking a finishing cut the carriage will be returned to start position and the resurfacing tool will be moved into a finishing-cut position; whereas in taking another heavy cut the carriage will be returned and the resurfacing tool will be reset in a new operative position. When the tool is to be reset for another heavy cut, the machine is stopped as by throwing the control means to "off" position, the carriage is partially returned to bring the tool into a position overlying the record, the

tool is then reset, after which the return of the carriage is completed and the control means is thrown to "on" position to restart the machine. At the completion of a record resurfacing the record is ejected from the machine, as by a suitable record-ejecting means provided for this purpose.

It is an object of my invention to prevent a change of record on the machine, subsequent to the completion of a record resurfacing operation, until the manipulatable control means for the machine is thrown to "off" position.

Another object of my invention is to prevent a change of record on the machine as mentioned above while the control means for the machine is in "on" position and the resurfacing tool is in operative position.

It is another object of my invention to compel the throwing of the control means for the machine to "off" position before the carriage is returned to take another first or heavy cut, the throwing of the control means to "off" position being, however, not required in the taking of a finishing cut.

It is another object of my invention to force the operator, at the completion of a resurfacing of a record on the machine, to throw the control means for the machine to "off" position in order to permit a further use of the machine. A feature of my invention is to cause the resurfacing tool to be released from operative position as an incident to such throwing of the control means to "off" position.

It is another object of my invention to lock the endgate in operative or mandrel-supporting position as an incident to the movement of the carriage into terminal position, and to automatically render the carriage locked against return movement when the same has reached its terminal position.

Another object is to render the lock on the endgate and the lock on the carriage each inoperative as an incident to the throwing of the manipulatable control means to "off" position and the return of the resurfacing tool from operative position.

Other and allied objects will more fully appear from the following description and the appended claims.

In the description of my invention reference is had to the following drawings, of which:

Figure 1 is a top plan view of a phonograph record resurfacing machine in which my invention is incorporated;

Figure 2 is a right-hand vertical cross-sectional

view taken substantially along the line 2—2 of Figure 1;

Figure 3 is a fragmentary front view of the mechanism of Figure 1, partly in section and showing an interlinkage system in accordance with my invention;

Figure 4 is a detailed view of a part of the mechanism of Figure 3, taken substantially along the line 4—4 of that figure; and

10 Figure 5 is a top view of the interlinkage system of Figure 3, taken substantially along the line defined by the bottom side of the base plate.

Reference being had to the figures there will be seen a phonograph record resurfacing machine

15 such as is commonly used to resurface phonograph records of the type employed in dictating machines, comprising a base plate 1 having a left-hand upright standard 2, an intermediate upright standard 3, right-hand upright standards

20 4 and 5, and an upright boss 6 directly to the right of the standard 5. Pivoted to the boss 6 is an endgate 7 biased into open position by a torsional spring 8 but normally held in closed position, as shown in Figure 1, by an endgate bolt

25 or latch 9 pivoted as at 10 to the right end portion 11 of a guide rail 12 extending laterally along the front of the machine. The endgate 7 carries a conically pointed stud 13 which together with a conically pointed stud 14 carried by the

30 standard 2 forms right and left thrust bearings for a shaft 15 extending laterally of the machine in parallel relation to the guide rail 12. The shaft 15 extends through an oversized hole 16 in the intermediate standard 3, and is provided

35 with a mandrel 17 for supporting a cylindrical record 18 to be resurfaced. To mount or remove a record from the mandrel 17 the endgate 7 is first opened to free the right end of the mandrel; during the time the endgate is open the shaft 15

40 is intermediately supported by the intermediate standard 3 and is retained in engagement with the conical stud 14 by the contact of a collar 19, secured to the shaft by a screw 19', with the left side of the intermediate standard 3.

45 Parallel to the shaft 15 and guide rail 12 is a longitudinal rod 20 supported by the left and right standards 2 and 5. Slidably and tiltably mounted on the rod 20 is a carriage 21 having a sleeve 22 embracing the rod. As shown in

50 Figure 2 the carriage is provided with an arm 23 curved forwardly over the mandrel 17 and terminating in a shoe 23' which normally slidably rests on the guide rail 12. The carriage is steadily moved or fed in a leftward direction

55 across the mandrel (as from a start position at the right end of the mandrel to a terminal position at the left end of the mandrel) by a laterally extending feed screw 24 rotatably supported by the left and right standards 2 and 4.

60 Secured to the carriage sleeve 22 by the pins 25 is a resilient and rearwardly extending arm 26 carrying a feed nut 27 which normally engages the underside of the feed screw. When the carriage arm is tilted upwardly, as until a

65 rearwardly and downwardly extending post 28 on the carriage impinges against a laterally extending ridge 29 on the base plate (see Figure 2), the feed nut 27 is moved downwardly out of engagement with the feed screw; thus while the carriage is so tilted it may be manually moved, at will, across the mandrel. When the carriage arm 23 is, however, resting on the guide rail 12, with the feed nut 27 being in engagement with the feed screw 24, a rotation of the feed screw

70 will cause a slow steady movement of the carriage. In order that such feeding of the carriage will occur coincidentally with a rotation of the mandrel the feed screw is provided with a pulley 30 which is coupled, as by a belt not shown, to a pulley 31 on the mandrel shaft 15. 5

In the operation of the machine the mandrel 17 and feed screw 24 are turned in a clockwise direction, the direction of thread on the feed screw being such as to then cause a leftward feed of the carriage. 10

On the right side of the carriage there is an extension 32, square-shaped as viewed from the end, which substantially overlies the rod 20. The extension 32 carries a resurfacing tool 33 comprising a knife blade 34 mounted on a knife bar 35 which is slidably supported by the extension 32 for movement towards and away from the record. The means for setting the resurfacing tool into operative position—a position of the tool in which the knife blade 34 engages the record—and for releasing the same may be of a well known construction such as is disclosed in Brown Patent No. 2,137,383, issued November 22, 1938, and entitled "Record shaving machine."

20 A tool-setting mechanism of the abovementioned type is sufficiently described in the present instance as follows: A cap 36 is slidably mounted on the extension 32, guided by a guide rod 37, and coupled to the knife bar 35 by a compression spring 38 coiled about the knife bar between the

30 cap 36 and a shoulder 35' on the knife bar, this coupling serving to yieldably move the knife bar downwardly towards the record when the cap 36 is moved downwardly. The cap 36 is urged upwardly by a spring 39 coiled about the guide rod 37, but upward movement of the cap 36 relative to the bar 35 is limited by a head 40 on the bar. By reason of the upward biasing of the cap 36 the knife bar is normally maintained in inoperative position, this position being defined by the

40 contact of a collar 41 on the bar 35 with the underside 32' of the extension 32. The setting of the tool 33 is controlled by a lever 42 pivoted on the right side of the extension 32 and having a short arm 43 which is coupled to the cap 36 by

45 an angular link 44, the link being pivoted to the arm 42 by a pin 45 and to the cap 36 by a pivot screw 46. As the lever is swung forwardly in a counter-clockwise direction the cap 36 and knife bar 35 are moved downwardly, the tool

50 being moved into operative position relative to the record; in the terminal movement of the lever a lock 47, described in detail in the abovementioned Brown patent, is rendered operative to hold the tool in operative position, thereby setting the tool. Such forward or setting movement of the lever 42 is limited to the position shown

55 in Figure 2 by the impingement of the link 44 with the hub 42' of the lever. When the lever is in this most forward position the pin 45 is slightly past dead center with respect to the pivot axes of the lever 42 and the pivot screw 46.

60 The upward biasing force exerted on the cap 36 then causes the lever 42 to be urged in a counter-clockwise direction—the direction in which the lever 42 is moved to set the tool—but movement of the lever in such direction is prevented by the

65 contact of the link 44 with the hub 42'. Thus when the lever 42 reaches such limited position, the lever is releasably held there to maintain the tool in operative position. When the lever 42 is,

70 however, tripped, or moved slightly in a clockwise direction, to return the pin 45 across the dead center line aforementioned, the lever 42 is returned and the cap 36 is moved upwardly, as

75

80

85

90

by the spring 39, to render the lock 47 inoperative and thereafter to return the tool to inoperative position.

In the operation of the machine the resurfacing tool is first set into operative position while the carriage 22 is in an intermediate position overlying the record, the carriage is then moved into start position, and the machine is then started to cause mandrel rotation and a feeding 10 of the carriage along the mandrel. As the carriage is thus fed along the mandrel a first or heavy cut is taken from the record, the cut-away layer—commonly known as shaving chips—being carried by a chip-chute 48 downwardly 15 through an opening 48' in the base plate.

The driving means for the machine—the means for feeding the carriage and rotating the mandrel—may comprise a suitable electrical motor M which may be located beneath the base plate 20 and be coupled to a pulley 49 on the mandrel shaft 15 by a belt (not shown) which may pass through an opening 50 in the base plate. To control the motor M there is provided an auxiliary switch 51 and a main switch 52 which are 25 serially connected in a power supply circuit 53 for the motor, the circuit 53 being adapted to make connection with a suitable source of power by way of a plug 54, as is schematically shown in Figure 2.

80 The auxiliary switch 51 comprises a casing 55 preferably of suitable insulating material, secured by the screws 56 to the top side of the base plate in the rear left-hand portion thereof. This casing insulatedly carries left and right 35 forwardly extending contact springs 57 and 58 mounted in cantilever fashion on a stack 59 and biased into contact with each other. In the rearward side of the casing there is an opening 60 from which extends a cable 61 by which the switch is connected in the circuit 53, and in the forward side of the casing there is an opening 62 from which extends an insulating bar 63 secured to the left contact spring 57. Secured to the rearward part of the carriage by a screw 45 64' is a downwardly extending arm 64 which, as the carriage moves into its terminal position impinges against the bar 63 to move the contact spring 51 leftwardly out of contact with the contact spring 58, thereby opening the circuit 53 50 to stop the machine.

The main switch 52 is preferably of the single-pole single-throw toggle variety adapted to snap into its "on" and "off" positions and is mounted on the underside of the base plate in the front 55 right-hand portion thereof. This switch is controlled by a forwardly extending control lever 65 having a shaft 65' extending downwardly through a boss 66 in the base plate. Secured to the lower end of the shaft 65' by a shoulder screw 67 is a plate 68 having a rearwardly extending arm 69 carrying a slotted, pivoted stud 70 through which slidably passes an actuating arm 71 of the switch 52. When the control lever 65 is rocked leftwardly and rightwardly the arm 71 is moved rightwardly and leftwardly to place the switch in its respective "on" and "off" 65 positions, the arm 71 snapping into its leftward and rightward positions by reason of the toggle nature of the switch.

70 When the carriage is moved into its terminal position, as at the completion of a cut on the record, the machine is stopped by the switch 51 (as above explained), thereby permitting immediate inspection of the record. When the carriage is returned from its terminal position the

switch 51 closes, by reason of its biasing, to start the machine unless, of course the switch 52 is thrown to "off" position prior to the return of the carriage. Whether or not the switch 52 will be first thrown to "off" position is, in accordance 5 with my invention as hereinafter described, dependent upon the action to be performed subsequent to the completion of the first or heavy cut on the record. In the normal use of the machine there are three actions which may be 10 performed at the completion of such first cut on the record: the taking of another cut on the record of a light or finishing character to obtain an added smoothness of the record, the taking of another heavy cut, or the ejecting of a record 15 from the machine. The means for taking a light or finishing cut on the record is now described.

On the carriage arm 23 there is provided a finishing-cut controlling means operable to move or advance the set tool a slight distance towards 20 the record. This finishing-cut controlling means comprises a short rod 72 mounted for pivotal movement about its longitudinal axis and extending through the shoe 23' of the carriage in parallel relation to the guide rail. The rod 72 25 projects radially along its length below the shoe 23' throughout a minor portion of its periphery so that the carriage arm 23 is normally supported by the guide rail by way of the rod 72. The rod 72 is, however, provided with a flat 73 throughout 30 its length. When the rod is turned to bring the flat 73 into contact with the guide rail, the carriage arm is lowered slightly to advance the tool towards the record. On the rod 72 there is a 35 forwardly extending bracket 74 by which the rod may be manually turned. When the bracket 74 is in the position shown in Figure 2, the flat 73 is off the guide rail 12 and the finishing-cut controlling means is in inoperative position; when the bracket is, however, moved upwardly 40 into a position such as is indicated in dash-dot lines in Figure 2, the flat 73 is in contact with the guide rail and the finishing-cut controlling means is in operative position.

When a record is to be removed from the machine the endgate is first opened and then there is operated a record-ejector, well known in the art, which comprises a handle 75 integral with a hub 75' and an upstanding arm 76, the hub being secured by a screw 77 to a short rod 78 50 pivotally supported at one end by the guide rail 12 and at the other end by the intermediate standard 3. The arm 76 carries a shoe 79 bearing a cushion 80 lying directly to the left of the record. The record-ejector is normally maintained in an unoperated position, shown in Figure 1, by a coil spring 81. In the operation of the ejector the handle 75 is raised against the force of the spring 81 so as to move the cushion 80 rightwardly against the record to push the record off the mandrel.

Usually operated coincidentally with the record-ejector is a mandrel brake. This brake comprises an arm 82 pivoted on the rod 78 and bearing a shoe 83. The arm is coupled to the arm 65 76 of the record-ejector by a spring 84 coiled about the hub 75' of the record-ejector and hooked at one end about a forwardly extending pin 85 on the arm 82 and at the other end about a rearwardly extending pin 86 which is on the arm 76 to the right of the pin 85, the pins 85 and 86 being thus normally urged together. By means of this resilient coupling of the arm 82 to the arm 76 the shoe 83 is yieldably moved into contact with the mandrel to retard the rotation 75

of the mandrel as the record-ejector is operated.

Of the three actions aforementioned which

- 5 may be selectively performed at the completion of a first or heavy cut on the record only the taking of a light or finishing-cut does not involve the release of the resurfacing tool from its original setting. When a finishing cut is to be taken it is only necessary to move the bracket 74 upwardly to render the finishing-cut controlling means operative, tilt the carriage upwardly and then manually return it to its start position. When this is done the machine is restarted by the closing of the switch 51, the switch 52 having been left in "on" position. When the carriage is lowered upon the guide rail in its start position it will be next fed leftwardly across the record and the record will be rotated to effect the finishing-cut operation. However, if it is desired to take another first or heavy cut on the same record or to eject the record so that another may be mounted on the machine to be resurfaced, the resurfacing tool will in each case have to be released so that it may be later reset. It is also necessary that the switch 52 be thrown to "off" position so that the record will not be set in rotation when the carriage is returned from its terminal position for the purpose of placing the tool in a position overlying the record to permit the resetting of the tool. It is particularly important when there has been a change of record on the machine that both the tool be released to inoperative position from its prior setting and that the switch 52 be thrown to "off" position before the carriage is returned to reset the tool in order to avoid possible scraping of the tool on the record in the return of the carriage, such scraping being particularly likely to occur whenever the newly mounted record is of greater diameter than the preceding record. In accordance with my invention, when a first or heavy cut has been taken on the record the operator is compelled to throw the switch 52 to "off" position and to release the tool from operative position before he may make a change of record on the machine or return the carriage to permit a resetting of the tool, this compelling means being, however, arranged to permit the carriage to be returned for the taking of a finishing cut on the record, as hereinafter explained.
- 35 The compelling means abovementioned may be in the form of means for locking the endgate in a mandrel-supporting position and of means for locking the carriage in a terminal position, the latter locking means being rendered inoperative by the movement of the finishing-cut controlling means to operative position so as to permit the taking of a finishing cut, but each of the locking means being rendered inoperative when the switch 52 is thrown to "off" position. In order that the tool will be released from operative position when each of the above locking means is rendered inoperative, a tool release is effected as an incident to the throwing of the switch 52 to "off" position. A means for so releasing the tool from operative position is disclosed in Heunlich Patent No. 2,095,332, issued October 12, 1937 and entitled "Record shaving machines".
- 50 A tool-releasing means of the form above-mentioned comprises a link 87 carrying a pin 88 in its forward end portion which engages a cam slot 88' provided in a rightwardly extending portion 89 of the plate 68, the link extending rearwardly along the right side of the machine beneath the base plate to pivotally connect with a right arm 90 of a lever 91 pivoted by a screw
- 55 92 to a boss 93 extending down from the base plate. A left arm 94 of the lever 91 is pivotally connected to the right end of a bar 95 which extends laterally of the machine along the rear edge of the opening 48' slightly within this opening. The bar 95 is supported at its left end by a link 96 pivoted by a pin 97 to the bar and by a screw 98 to a boss 99 extending down from the base plate, the link 96 and arm 94 forming a pair of parallel motion supports for the bar 95 to permit the bar to move forwardly and rearwardly in parallel movement.
- 60 On the right side of the carriage 21 there is pivotally supported, by a relatively long shoulder screw 100, a lever 101 best shown in Figure 2. The lever 101 operatively connects the bar 95 with the tool-setting lever 42 and comprises a lower vertical portion 102 slidably contacting the front edge of the bar 95, a central semi-circular portion 103 curved about the carriage sleeve 20 rearwardly thereof and pivoted at its upper end on the shoulder screw 100 adjacently of the right side of the carriage, a bail portion 104 extending along the screw 100, and a forwardly extending arm portion 105 pivoted on the outer end of the screw 100 and terminating at a point directly below the arm 43 of the tool-setting lever.
- 65 The cam slot 88' is arc-shaped and has at its rearward end an inwardly extending notch 106 in which the pin 88 is normally retained, as whenever the lever 65 is in a leftward position to place the switch 52 in "on" position, by a tension spring 107 which urges the link 87 leftwardly and forwardly. The link 87 extends forwardly and leftwardly from the pin 88 and terminates in a cam face 108 adapted to impinge against the boss 66 when the control lever 65 is moved rightwardly to place the switch 52 in "off" position. In the first portion of such movement of the control lever the pin 88 is held by the spring 107 in the notch 106 so that the link 87 will be moved rearwardly, such movement of the link causing a forward movement of the bar 95 and, by the contact of the bar with the lever 101, a clockwise movement of the lever 101. When the lever 101 is so moved its arm portion 105 impinges upon the arm 43 of the tool-setting lever to impart a "tripping" or clockwise movement of the tool-setting lever, thereby releasing the tool from operative position. In the further movement of the control lever 65 to place the switch 52 into "off" position the cam face 108 impinges against the boss 66 to limit the leftward movement of the link 87, the pin 88 being then moved out of the notch 106. When the pin 88 is free of the notch 106 the link 87 is moved forwardly by the spring 107, with the pin 88 coming to rest in the forward end portion of the cam slot 88', the forward position of the link 87 being defined by the engagement of a lug 94' on the arm 94 with the rear edge of the bar 95.
- 70 In the leftward movement of the control lever 65 to place the switch 52 into "on" position, the pin 88 slides rearwardly relative to the cam slot 88' and comes to rest in the notch 106, the bar 95 remaining stationary. Thus it is seen that a throwing of the switch 52 from "off" to "on" position will not disturb a prior setting of the tool.
- 75 The means for locking the carriage in its terminal position comprises a vertically disposed latching member 109 at the left end of the guide rail 12 (see Figures 3 and 4). This latching member is provided at its upper end with a catch 109' arranged to overlie the left end of the rod 72 in the carriage shoe 23' when the carriage is in its

terminal position, thereby locking the carriage arm 23' against upward tilting. Such locking of the carriage against upward tilting of its arm renders the carriage locked against manual return to its start position as because of the engagement of the feed nut 27 with the feed screw 24. The latching member 109 is pivoted by a pin 110 to an arm 111 turned up from a bar 112 which extends laterally of the machine below the base plate, the arm 111 passing through an opening 113 in the base plate to the left of the guide rail 12. The latching member 109 is normally retained in an operative or latching position—a position in which the member is substantially vertical as shown in Figure 4—by a tension spring 114 connected between a pin 115 on the latching member and a pin 116 on the arm 111, the operative position of the latching member being defined by the contact of the latching member with a stop lug 117 turned over from the arm 111. The bar 112 is slidably mounted for limited movement laterally of the machine by means of a pair of left and right shoulder screws 118 and 119 which respectively pass through slots 118' and 119' in the bar to thread into the respective bosses 118'' and 119'' extending down from the base plate. This slideable mounting for the bar 112 is provided in order that the bar may be moved by the terminal movement of the carriage, as by the contact of the carriage shoe 23' with the catch 109', to cause a locking of the endgate 7 in a closed or mandrel-supporting position, as is hereininafter described.

The locking of the endgate may very suitably be effected by a locking of the endgate latch 9 in operative position. The locking means for the endgate latch 9 comprises a slide 120 which is mounted on the back side of the guide rail 12 by means of a pair of shoulder screws 121 which pass through slots 121' in the slide to respectively thread into a pair of bosses 121'' which extend rearwardly of the guide rail. The slide 120 is disposed at the level of the endgate latch 9 and has its right end portion 120' offset slightly to the rear and terminating at a point slightly to the left of the pivot 19 of the endgate latch 9. On the shaft 9' of the endgate latch there is provided an extension 9'' which is just free from the end portion 120' of the slide 120 when the slide is in its most leftward position, as is shown in Figure 1. When the slide 120 is, however, moved rightwardly, while the endgate latch is in operative position, the end portion 120' of the slide engages the extension 9'' to lock the latch.

In accordance with my invention the locking means for the endgate is, in particular, to be effective whenever the carriage is in its terminal position. I may therefore render this locking means effective by the terminal movement of the carriage. In order that the locking means for the endgate will be so controlled there is provided a bar 122 which is disposed, partially along its length, directly below the bar 112. The bar 122 is slidably mounted for movement laterally of the machine, the same as the bar 112, the bar being slidably retained to the bar 112 by a shoulder screw 123 which passes through a slot 124 in the bar 122 to thread into the bar 112 and being also slidably supported by the screw 119 which passes through a slot 125 in the bar 122. Interposed between the bar 122 and the bar 112 are the spacers 126 and 127 respectively embracing the screws 123 and 119. The bar 122 is urged leftwardly relative to the bar 112 by means of a tension spring 128 connected between the bar 122 and a pin

128' on the bar 112, the leftward movement of the bar 122 relative to the bar 112 being limited by the contact of the screw 123 with the end of the slot 124, as shown in Figure 5. At the right end portion of the bar 122 is a pair of rearwardly extending jaws 129 forming a socket 130. In this socket there slidably fits the lower end 131' of a vertically disposed lever 131. This lever passes through an opening 133 in the base plate, is pivoted as at 134 to a boss 135 on the back side of the guide rail 12, and has its upper end 131'' slidably fitting in a socket 136 provided in the bar 120. Thus when the bar 112 is moved leftwardly by the terminal movement of the carriage, as hereinbefore mentioned, the bar 122 is also moved leftwardly, as because of the spring 128. When the bar 122 is so moved the lever 131 is rocked to move the slide 120 rightwardly into a position to lock the endgate latch 9.

At the completion of a cut on the record it is seen that the machine is automatically stopped, the carriage is locked in its terminal position and the endgate is locked in its closed position. To permit the taking of a finishing cut the carriage lock is rendered inoperative by the movement of the finishing-cut controlling means to operative position as by means of a small cam 137 (see Figure 2) secured, as by welding, to the left side of the bracket 14 of the finishing-cut controlling means. When the carriage is in its terminal position with the finishing-cut controlling means in inoperative position the cam 137 is just free from a cam face 138 provided on the catch 109' of the latching member 109. A movement of the finishing-cut controlling means to operative position will, however, cause the cam 137 to impinge upon the cam face 138 on the catch 109' and thereby move the latching member 109 in a counter-clockwise direction as it appears in Figure 4 to free the catch 109' from the rod 12. The carriage may then be returned to start position so that a finishing cut may be taken. When the carriage has been next fed to its terminal position, as at the completion of the finishing cut, the cam 137 will be disposed between the carriage shoe 23' and the catch 109'. This will cause the bar 112 to be moved further leftwardly than is normal, but such further movement of the bar 112 merely causes a small stretching of the spring 128 which couples the bar 112 to the bar 122.

While both the carriage and endgate become locked in their respective terminal and closed positions at the completion of a cut on the record, this locking of the carriage and endgate may be rendered inoperative by the throwing of the main switch 52 to "off" position, the release of the tool occurring as an incident to the throwing of the switch as hereinbefore described. The means for so rendering the locking means for the carriage and endgate each inoperative comprises a leftwardly extending arm 139 of the plate 68, on which arm there is provided an upright pin 140 which lies to the left of a forwardly extending cam arm 141 on the bar 122. When the carriage and endgate are locked the bar 122 is in its leftward position, the pin 140 then being in contact with the cam arm 141, as shown in Figure 5. When the control lever 65 is moved rightwardly to throw the main switch 52 to "off" position the bar 122 is moved rightwardly by the contact of the pin 140 with the cam arm 141, the spring 128 then stretching because the bar 112 is then retained by the carriage. Such rightward movement of the bar causes the slide 120 to be moved leftwardly free from the extension 9'', thereby

unlocking the endgate latch 9; moreover, as the bar 122 is moved rightwardly a cam 142, provided on the end of an arm 143 extending leftwardly from the bar 122, contacts an arm 144 extending downwardly from the latching member 109 (see Figures 4 and 5), thereby turning the latching member 109 in a counter-clockwise direction to unlock the carriage from its terminal position.

10. Although I have herein shown and described one embodiment of my invention, it will be understood that this embodiment is subject to many changes and modifications without departure from the scope of my invention, which I understand to express according to the following claims.

I claim:

1. In a phonograph record resurfacing machine having a mandrel for supporting a record to be resurfaced: the combination of a movable endgate retainable in a mandrel-supporting position; a tool-carriage movable along said mandrel into a terminal position; and means, operated incidental to the movement of said tool-carriage into terminal position, for locking said endgate in 25 its mandrel-supporting position.

2. In a phonograph record resurfacing machine having a record-supporting mandrel: the combination of a movable endgate for said mandrel; means for locking said endgate; a tool-carriage 30 movable relative to said mandrel; and means, operated by said tool-carriage, for rendering said endgate locking means operative.

3. In a phonograph record resurfacing machine having a record-supporting mandrel: the combination of a movable endgate for said mandrel; an endgate locking means; a tool-carriage movable along said mandrel; a control means for the machine having "on" and "off" positions; and means, jointly controlled by said tool-carriage and said control means, for controlling said locking means.

4. In a phonograph record resurfacing machine having a record-supporting mandrel: the combination of a movable endgate for said mandrel; an endgate locking means; a tool-carriage movable along said mandrel; a control means for the machine having "on" and "off" positions; means, controlled by the movement of said tool-carriage, for rendering said locking means operative; and means, controlled by said control means, for rendering said locking means inoperative.

5. In a phonograph record resurfacing machine having a record-supporting mandrel: the combination of an endgate for said mandrel retainable in a mandrel-supporting position; means for locking said endgate in said mandrel-supporting position; a tool-carriage movable relative to said mandrel into a terminal position; a control means for the machine having "on" and "off" positions; means, operated incidental to the movement of said tool-carriage into said terminal position, for rendering said locking means operative; and means, operated as an incident to the movement of said control means from "on" to "off" position, for rendering said locking means inoperative.

6. In a phonograph record resurfacing machine having a record-supporting mandrel: the combination of an endgate for said mandrel; endgate locking means; a tool carriage adapted to be fed and otherwise manually moved relative to said mandrel; means for locking said tool-carriage against manual movement; a control means for the machine having "on" and "off" positions; and means, controlled by said

control means, for controlling both said endgate locking means and tool-carriage locking means.

7. In a phonograph record resurfacing machine having a record-supporting mandrel: the combination of an endgate for said mandrel retainable in a mandrel-supporting position; means for locking said endgate in said mandrel-supporting position; a tool-carriage movable relative to said mandrel into a terminal position and returnable therefrom; means for locking said tool-carriage against return movement from said terminal position; a control means for the machine having "on" and "off" positions; and means, operated incidental to the movement of said control means to "off" position, for rendering both said endgate locking means and tool-carriage locking means inoperative.

8. In a phonograph record resurfacing machine having a record-supporting mandrel: the combination of a movable endgate retainable in a mandrel-supporting position; means for locking said endgate in said mandrel-supporting position; a tool-carriage; driving means for feeding said tool-carriage along said mandrel into a terminal position; means for stopping said driving means and for rendering said endgate locking means effective by the movement of said tool-carriage into said terminal position; means for locking said tool-carriage in said terminal position; manipulatable control means operable to start and stop said driving means when said tool-carriage is out of said terminal position; and means, controlled by said manipulatable control means, for rendering said tool-carriage locking means and endgate locking means inoperative.

9. In a phonograph record resurfacing machine having a record-supporting mandrel: the combination of an endgate; a latch for retaining said endgate in a mandrel-supporting position; a tool-carriage movable across said mandrel into a terminal position; means operated incidental to the movement of said tool-carriage into said terminal position, for locking said endgate latch in operative position; control means for the machine movable into "off" and "on" positions; and means, operated incidental to the movement of said control means to "off" position, for rendering said locking means inoperative.

10. In a phonograph record resurfacing machine having a record-supporting mandrel: the combination of an endgate; a latch for holding said endgate in a mandrel-supporting position; a carriage; a resurfacing tool on said carriage settable into operative position relative to a record on said mandrel; driving means for feeding said carriage across said mandrel into a terminal position; a pair of serially connected "on" and "off" switches for controlling said driving means; means for locking said latch in operative position; means for moving one of said switches to "off" position incidental to the movement of said carriage into terminal position; means for locking said carriage in said terminal position; and means, operated incidental to the throwing of the other of said switches to "off" position, for rendering the locking means for said latch and tool-carriage each inoperative, and for moving said tool out of operative position.

11. In a phonograph record resurfacing machine having a record-supporting mandrel: the combination of an endgate retainable in a mandrel-supporting position; means for locking said

endgate in said mandrel-supporting position; a resurfacing tool settable into operative position relative to a record on said mandrel; control means for the machine having "on" and "off" positions; and means, operated incidental to the moving of said control means to "off" position, for rendering said locking means inoperative and for causing said tool to be moved out of operative position.

12. In a phonograph record resurfacing machine having a record-supporting mandrel; the combination of an endgate movable into a mandrel-supporting position; a carriage movable along said mandrel into a terminal position; a

resurfacing tool on said carriage movable into operative and inoperative positions relative to a record on said mandrel; means for locking said carriage in said terminal position; means for locking said endgate in said mandrel-supporting position; means movable into "on" and "off" positions to control the operation of the machine; and means, controlled by said control means, for concurrently moving said tool to inoperative position and rendering both said endgate locking means and carriage locking means each inoperative.

CHARLES HUENLICH.
